(57) **CLAIM**

The ornamental design for a “fishing rod holder”, as shown and described.

DESCRIPTION

FIG. 1 is a right side perspective view of the fishing rod holder showing our new design;

FIG. 2 is a right side perspective view;

FIG. 3 is a left side perspective view;

FIG. 4 is a top perspective view, shown in a folded position; and,

FIG. 5 is a bottom perspective view, shown in a folded position.

The broken line showing of environment in FIGS. 1 and 3 is for illustrative purposes only and forms no part of the claimed design.

Our fishing rod holder is characterized by its ability to be folded as well serrations on the bottom surface.
